SWITCHING APPARATUS

Gottlieb Steiner, Solothurn, Switzerland, assignor to Scintilla Aktiengesellschaft, Solothurn, Switzerland, and to Scintilla Aktiengesellschaft, Berlin, Germany

Application April 9, 1931, Serial No. 528,992
In Germany March 10, 1930

4 Claims. (Cl. 123—148)

This invention relates to a switching apparatus, such as is used for controlling the electric ignition circuits of the engines of airplanes, in which the engines are put in operation successively with a starting magneto.

For distributing the high tension current of the starting magneto to the working magnetos it has been the usual practice hitherto to use a switch which was quite independent of the switching apparatus for controlling the ignition circuits of the working magnetos, that is to say, a separate switch was provided. This complicated the apparatus and increased its weight, points which are of great importance in airplanes.

According to the present invention this disadvantage is overcome by the member, the function of which is to distribute the high tension current of the starting magneto, to the working magnetos, being combined with the switching apparatus for the control of the ignition circuit of the working magnetos.

In the accompanying drawings a constructional example of the invention is shown. Figure 1 is a vertical section through the switching apparatus on line A—A of Fig. 2. Fig. 2 is a section on line B—B of Fig. 1. In Fig. 3 a diagram of connections is shown.

In Fig. 1 D₁ is the connecting terminal bolt for one of the working magnetos of one airplane engine, to which the contact spring E₁ is fixed, F₁ being the contact spring for the connecting terminal bolt J₁ of the second working magneto. G is a rotary switch of a known kind by means of which the working magnetos of all the airplane engines and of the starting magneto can be short-circuited. H₄ is one of the rotary switch structures of a known kind for controlling the ignition circuits of the working magnetos of the separate engines, by means of which one or other or both working magnetos of the airplane engine in question can be short-circuited. O is the common conductive bus bar in which the switches for the separate engines and the common short-circuiting switch are mounted. This conductive bar is mounted on an insulating plate K; on the outside of the latter is fitted the casing Y which is covered by the casing cover N.

The plan view according to Fig. 2 shows by way of example a switching apparatus for four airplane engines. H₁, H₂, H₃ and H₄ represent the separate switches for the individual engines and G the common short-circuiting switch. D₁—J₁ or D₂—J₂, D₃—J₃, D₄—J₄ respectively are the two connecting terminal bolts for the short-

circuiting cables of the two working magnetos provided for each engine. E₁, E₂, E₃, E₄ and F₁, F₂, F₃, F₄ are the contact springs which lead to the common short-circuiting switch G, while the contact springs L₁, L₂, L₃, L₄ and M₁, M₂, M₃, M₄ make contact with the separate switches for the different engines. D₅ is the connecting terminal bolt for the short-circuiting cable of the starting magneto DN, which is in contact through the contact spring E₅ with the common switch G. 10 O is the common bus bar. P is the supply terminal of the high tension current distributor, while from the terminals Q₁, Q₂, Q₃, Q₄ the high tension cables lead to the individual working magnetos. 15

The high tension current passes from the supply terminal P over the bar R into the current transmitting member S, which is mounted in the rotary switch member U made of insulating material, thence to the conducting piece T, to the outgoing terminal Q₁ and finally to the separate working magnetos. The switch G and the switches H₁, H₂, H₃, H₄ are each provided with a member for arresting the switches in the different switching positions, which member consists of a fixed notched plate V, a resilient notched plate W, which is fixed to the switch spindles and balls X. The resilient notched plate W serves the further purpose of pressing the rotary switch member G or H₁, H₂, H₃, H₄ against the common bus bar O, thus ensuring a good contact with the same for the mass of the machine. In an analogous manner the current transmitting piece S which is mounted in the rotary switch member U is pressed against the bar R, whereby a good contact is also established. 30

In Fig. 3 V₁, V₂, V₃, V₄ represent four internal combustion engines in accordance with the constructional example. N₁, N₂, N₃, N₄, N₅, N₆, N₇ and N₈ are the working magnetos provided for the separate engines, namely two for each engine. DN is the starting magneto and is connected to the supply terminal P. From the terminals Q₁, Q₂, Q₃, Q₄ of the high tension distributor switch connecting wires lead to the high tension distributing member of the working magnetos N₁, N₂, N₃, N₄, N₅ of the internal combustion engines. In this way one engine after another can be put in operation with the hand-operated starting magneto DN. G is a short-circuiting switch which is connected to the mass M of the machine and to which the short-circuiting cables of the hand-operated starting magneto and those of all the working magnetos lead. In this way it is possible with a single switch motion to short- 45

- circuit all the magnetos. H_1, H_2, H_3, H_4 are the switches for controlling the circuits of the working magnetos. By these switches one or other or both working magnetos can be short circuited.
- 5 An arrangement according to this invention constitutes considerable simplification of the apparatus for controlling the ignition circuits in the aeroplane engines.

What I claim is:

- 10 1. In a switching apparatus for controlling the ignition circuits of the booster and working magnetos of aeroplane engines, in combination terminal bolts, a common short circuiting switch structure centrically arranged, separate switch structures disposed around the latter, said terminal bolts being electrically connected to said common short circuiting switch structure and said separate switch structures, an insulating casing plate, a common current conducting bus-bar fixed to said insulating casing plate, said switch structures being journalled in said bus-bar, a casing ring, a high tension distributor switch structure arranged between two of said separate switch structures inside said casing ring, a casing cover enclosing all of said switch structures.
- 15 2. In a switching apparatus for controlling the ignition circuits of the booster and working magnetos of aeroplane engines, in combination terminal bolts, a common short circuiting switch structure, separate switch structures disposed around the latter, contact springs leading from said terminal bolts to said common short circuiting switch structure and said separate switch structures, an insulating casing plate, a common current conducting bus bar fixed to said insulating plate, said switch structures being journalled in said bus bar, a casing ring, a high tension distributor switch structure arranged between two of said separate switch structures inside said
- 20 casing ring, a casing cover enclosing all of said switch structure.
- 25 3. In a switching apparatus for controlling the ignition circuits of the booster and working magnetos of aeroplane engines, in combination terminal bolts, a common short circuiting switch structure, separate switch structures, disposed around the latter, contact springs leading from said terminal bolts to said common short circuiting switch structure and said separate switch structures, an insulating casing plate, a common current conducting bus bar fixed to said insulating plate, said switch structures being journalled in said bus bar, a casing ring, a high tension distributor switch structure arranged between two of said separate switch structures inside said
- 30 casing ring, a casing cover enclosing all of said switch structure.
- 35 4. In a switching apparatus for controlling the ignition circuits of the booster and working magnetos of aeroplane engines, in combination terminal bolts, a common short circuiting switch structure, separate switch structures, disposed around the latter, contact springs leading from said terminal bolts to said common short circuiting switch structure and said separate switch structures, an insulating casing plate, a common current conducting bus bar fixed to said insulating plate, said switch structures being journalled in said bus bar, a casing ring, a notched plate fixed to said insulating casing plate, said switch structures being arranged between said insulating casing plate and said notched plate, spindles of said switch structures, resilient plates fixed to said spindles of the switch structures one for each of the latter, balls fixed to said resilient plates and adapted to engage the notches of said notched plate, said spindles being journalled in said common conducting bus bar and pressed against the latter by means of said resilient plates, a casing cover enclosing said switch structures and said notched plate.
- 40 5. In a switching apparatus for controlling the ignition circuits of the booster and working magnetos of aeroplane engines, in combination terminal bolts, a common short circuiting switch structure, separate switch structures, disposed around the latter, contact springs leading from said terminal bolts to said common short circuiting switch structure and said separate switch structures, an insulating casing plate, a common current conducting bus bar fixed to said insulating plate, said switch structures being journalled in said bus bar, a casing ring, a notched plate fixed to said insulating casing plate, said switch structures being arranged between said insulating casing plate and said notched plate, spindles of said switch structures, resilient plates fixed to said spindles of the switch structures one for each of the latter, balls fixed to said resilient plates and adapted to engage the notches of said notched plate, said spindles being journalled in said common conducting bus bar and pressed against the latter by means of said resilient plates, a high tension current supply bar cast integrally with said insulating casing plate, a high tension current transmitting bar, a rotary insulating body journalled in said insulating casing plate, said transmitting bar being cast integrally with the rotary insulating body, a plurality of high tension conducting bars arranged around said rotary insulating body and cast integrally with said insulating casing plate, said current transmitting bar being adapted to transmit the current from the current supply bar to said plurality of conducting bars, a casing cover enclosing said switch structures and said notched plate.

GOTTLIEB STEINER.
